UNITED STATES PATENT OFFICE
CERTIFICATE OF CORRECTION

Design No. 208,963

October 17, 1967

Stuart M. Lenz et al.

It is hereby certified that error appears in the above numbered patent requiring correction and that the said Letters Patent should read as corrected below.

In the grant, lines 3 and 4, for "of Plaza, New York, a corporation of Delaware," read -- of New York, N. Y., a corporation of New Jersey, --; in the heading to the drawings and printed specification, line 5, for "Plaza, N. Y., a corporation of Delaware" read -- New York, N. Y., a corporation of New Jersey --.

Signed and sealed this 12th day of November 1968.
